DESIGN FOR A COMBINATION GRILL AND INCINERATOR

Wilton F. Reichelderfer, Oakwood, Ohio

Application March 10, 1947, Serial No. 137,484

Term of patent 7 years

(Cl. D81—1)

To all whom it may concern:

Be it known that I, Wilton F. Reichelderfer, a citizen of the United States, residing at Oakwood in the county of Montgomery and State of Ohio, have invented a new, original, and ornamental Design for a Combination Grill and Incinerator, of which the following is a specification, reference being had to the accompanying drawing, forming part thereof.

In the drawing:

Fig. 1 is a front elevational view of the combination grill and incinerator, showing my new design;

Fig. 2 is a side elevational view;

Fig. 3 is a rear elevational view; and

Fig. 4 is a top view.

I claim:

The ornamental design for a combination grill and incinerator, as shown.

WILTON F. REICHELDERFER.
